US0D1045156S

(12) **United States Design Patent** (10) Patent No.: **US D1,045,156 S**
(45) Date of Patent: ** Oct. 1, 2024

(54) **LENS MODULE FOR AUTOMOTIVE LAMPS**

(71) Applicants: **Hyundai Motor Company**, Seoul (KR); **Kia Corporation**, Seoul (KR)

(72) Inventors: **Chang Hoon Choi**, Suwon-si (KR); **Dai Sung Kim**, Gunpo-si (KR); **Byeong Ho Jeong**, Yongin-si (KR); **Won Suk Kang**, Hwaseong-si (KR)

(73) Assignees: **Hyundai Motor Company**, Seoul (KR); **Kia Corporation**, Seoul (KR)

(**) Term: **15 Years**

(21) Appl. No.: **35/519,877**

(22) Filed: **Jul. 27, 2023**

(80) **Hague Agreement Data**

Int. Filing Date: **Jul. 27, 2023**

Int. Reg. No.: **DM/231712**

Int. Reg. Date: **Jul. 27, 2023**

Int. Reg. Pub. Date: **Feb. 2, 2024**

(30) **Foreign Application Priority Data**

Feb. 10, 2023 (KR) 30-2023-0005003
